UNITED STATES PATENT OFFICE.

RICHARD ZIESCHANG, OF LONDON, ENGLAND, ASSIGNOR OF ONE-HALF TO WILBERT EDWARD STRATTON, OF LONDON, ENGLAND.

MOP AND WRINGING ATTACHMENT THEREFOR.

1,426,440.

Specification of Letters Patent. Patented Aug. 22, 1922.

Application filed May 29, 1920. Serial No. 385,261.

To all whom it may concern:

Be it known that I, RICHARD ZIESCHANG, a subject of the King of Great Britain, and residing at London, England, have invented 5 certain new and useful Improvements in Mops and Wringing Attachments Therefor, of which the following is a specification.

This invention relates to mops provided with wringing appliances for use in wringing out moisture from the mop head. It is the object of the invention to provide an improved appliance of this character wherein the wringing appliance is in the form of a box with flaps or shutters, such that the 15 whole wringing appliance can be drawn back along the mop stem to expose the head for use, or can be moved down over the head, and the flaps or shutters closed whenever wringing out of moisture is to be effected. 20 Other objects of the invention are to provide convenient catches and release devices therefor, whereby the wringing appliance is held either open or closed as required, and is released from the closed position.

25 The invention is illustrated in the accompanying drawings, wherein:

Figure 1 shows the complete mop with its head extended for use.

Figures 2 and 3 are views to a larger 30 scale showing in front and side elevation, the wringing attachment closed over the mop head.

Figures 4 and 5 are corresponding views 35 to Figures 2 and 3, of the mop with the closed wringing attachment in section.

Figure 6 is a similar view to Figure 5, but showing the flaps opened.

Figure 7 is an external view of a modified form of the mop and wringer, showing 40 the mop head enclosed in the box.

Figure 8 is a sectional view, drawn to a larger scale, showing the catch and release mechanism of the form of construction shown in Figure 7.

45 Figure 9 is a detail view of the wringing box and mop head drawn to a larger scale.

Figure 10 is an end view of the wringing box with the flaps closed.

Referring first to Figures 1 to 6, *a* is the 50 mop head, consisting of a tuft or tufts of textile material attached to a cap *b* secured to the end of a stem *c*. Upon this stem slides a sleeve *e* carrying at its end the box or wringer *d*. This box is made of metal, preferably 55 with corrugations pressed in the sides thereof

as shown, in order to strengthen it and to give an effective wringing action when the mop is twisted within it. Upon the sleeve *e* works an outer sleeve *f*, which is normally pressed up by a spring *g* acting between flanges on the sleeves *e* and *f*. The sleeve *f* carries lugs *h* to which are connected links *k*, and the other ends of these links are connected to the flaps *n* which serve to close the box *d* when used for wringing out the 60 mop head *a*. The flaps *n* are carried by end pieces *m* pivoted at *l* on the ends of the box *d*. The flaps *n* are corrugated for wringing purposes, and are perforated as shown to allow of the escape of the water wrung 65 out. The sleeve *f* has an extension *o* at the top, inside which is a spring tongue *p*; when the sleeve *f* is pressed down against the action of spring *g*, this tongue engages with a notch in sleeve *e*, so holding the flaps *n* 70 closed as in Figure 5. A sliding ring *q* working on sleeve *e*, has a tapered end which serves, when pressed down, to engage with outwardly bent horns on the tongue *p*, pressing it back to disengage it from the 75 notch, and so allowing sleeve *f* to rise again and the flaps *n* to open, under the action of spring *g*. The ring *q* is a short section of tubing with an enlarged head, this tubing being a free sliding fit on sleeve *e*, but 80 indented at one or more places to hold it by friction against unintentional movement. A flange or collar on the sleeve *e* carries a projecting handle *s* whereby the sleeve and the box *d* thereon are held against turning 85 during the wringing operation. The end of sleeve *e* above this is arranged to engage in any suitable way with the hand-grip *t* on the stem *c*, in order to hold up the wringing attachment when not in use. For example, spring tongues *u* in the grip *t*, with little knobs thereon which engage in holes or notches at *v* in the sleeve *e* when it is pulled up, will serve this purpose. The engagement is released readily when required 90 by pressing down the sleeve *e* with sufficient pressure away from the grip *t*. Buffers or rollers *w* on the corners of the end pieces *m* of flaps *n* prevent risk of damage being done by such corners striking against objects when the mop is in use.

The method of use is as follows:—Assuming the mop head *a* to have been dipped in water or other liquid, while the head is exposed as in Figure 1, the grip *t* is held and 100

sleeve e is pressed down causing the mop to be drawn into the box d . The flaps n are closed, by pressing down the sleeve f , the spring g is compressed, while sleeve f 5 slides over sleeve e , until the flaps n are closed and tongue p engages with the notch in sleeve e . Then the wringing is effected by pressing down the grip t towards handle s so as to squeeze the end of the mop against 10 the flaps n , and twisting the grip t relatively to handle s , so as to turn the mop head a in the box d , whereby it is twisted and wrung out effectively. When this is done, ring q is pressed down to release tongue p and 15 allow spring g to lift sleeve f , opening the flaps n , whereupon the sleeve e can be pulled up by continued upward pulling on extension o of sleeve f , or on handle s until the catches u engage with sleeve e . The mop 20 head is then exposed again as in Figure 1 and ready for use, in a damp condition but with the surplus moisture wrung out. After use, it is washed out in a bucket for example, and then wrung out as above described 25 to make it ready for further service.

In the modified form of the mop and wringer shown in Figures 7 and 8, the box d_1 of the wringer is made shorter, and approximately square in section, but with the 30 corners chamfered. The mop head a is secured in a dome-shaped cap b_1 by stitching through holes at b_2 , while the cap itself is secured by a pin c_2 on the end of the tubular mop stem c_1 . The box d_1 is connected to the 35 sleeve e_1 by arms e_2 . The flaps or shutters n_1 are made with fingered end plates and with round bars extending across the opening of the box when the flaps are closed. They are pivoted at n_2 on the box, and 40 connected by links or reins k_1 of springy metal, to the sleeve f_1 . Lugs e_3 on the sleeve e_1 serve to guide the reins k_1 and to prevent turning of the sleeve f_1 .

The sleeve e_1 has a collar e_4 against which 45 the spring g_1 bears, and it also has a projection p_1 against which the spring catch p_2 bears. This catch is shown as being formed on the end of one of the reins or links k_1 by which the shutters n_1 are opened and 50 closed, the member k_1 being extended for this purpose beyond its attachment to the sleeve f_1 , and being arranged to project through a slot in the said sleeve. Beyond this slot the sleeve f_1 has a flange f_2 to which 55 is attached a grip or handle f_3 . This grip is held while the mop stem c_1 is being turned to wring out the mop head in the box d_1 . Over the stem c_1 slides a releasing sleeve q_1 60 projecting beyond the grip f_3 , and enlarged at its lower end so as to slide over the upper end of the sleeve e_1 . A lateral projection q_2 on the sleeve q_1 has an inclined face whereby it can lift out of action the spring catch p_2 when sleeve q_1 is pressed down- 65 wardly. Beyond this projection the sleeve

is slotted to allow of the passage of the projection p_2 therethrough, and the end of sleeve q_1 has a flange q_3 for the upper end of spring g_1 to bear against. This flange in turn rests against an internal flange f_4 in 70 the sleeve f_1 . In order to provide an upward spring pressure tending to raise sleeve f_1 and sleeve q_1 severally, the sleeve f_1 is provided with a block f_5 in front of its flange f_4 at one side, by which one edge of 75 the spring g_1 is canted as shown. The result is that some spring pressure is opposed to the pressing down of sleeve q_1 to release catch p_2 , and a sufficient residual spring pressure is left against the block f_5 serving 80 to raise sleeve f_1 when released, and to prevent the re-engagement of catch p_2 with projection p_1 so long as sleeve q_1 is held. In this way a single spring is made to serve several different purposes. 85

In use, after the mop has been dipped in water it is drawn up into the box d_1 by holding the grip f_3 in one hand, and drawing up the stem c_1 with the other. This movement is continued after the mop head has come 90 to rest in the box and the stem c_1 can rise no further in sleeve e_1 . The further movement draws up sleeve e_1 inside sleeve f_1 until the catch p_2 engages projection p_1 when the flaps or shutters n_1 will have been closed. 95 Wringing is then effected by twisting the mop stem c_1 and pressing it down so that the mop head is pressed against the bars of the shutters n_1 . In order to open out the mop again, the hand with which the grip f_3 was 100 held is now used to grip the sleeve q_1 and to push it down. This releases the catch p_2 , and when q_1 is released the shutters spring open under the action of spring g_1 raising sleeve f_1 . The mop stem c_1 can now be 105 pushed down to expose the mop head to any required extent, and to enable the mop to be used for cleaning or polishing and so forth. The top of the sleeve q_1 will engage in the socket at the lower end of the grip f_3 if desired in order to hold the box d_1 raised with the mop head projecting to its fullest extent. 110

Although the mop and wringing attachment have been described as if they were always made and sold as a complete article, yet it will be apparent that the wringing attachment may be sold separately from the mop, and may be used with existing mop heads and stems in so far as such mop heads 115 have stems of a convenient size, such as that of the stem c in Figures 1 to 6, or the stem c_1 of Figures 7 and 8. The invention is not limited therefore to the combination of the mop and the wringing attachment but it includes also the wringing attachment per se. Various of the details of construction of the wringing attachment may be modified without departing from the spirit of the invention. The mop head also may be made of 120 125 130

any suitable material and a mop head of textile material has only been referred to for the sake of example.

Having thus described my invention, 5 what I claim as new and desire to secure by Letters Patent is:—

1. The combination of a stem and a mop head thereon with a sleeve sliding on said stem, a casing carried by said sleeve into 10 which casing the mop head can be drawn, flaps carried by said casing and adapted to close over the open lower end thereof, a second sleeve sliding over the first sleeve, and connections from said second sleeve to 15 said flaps whereby movement of the second sleeve over the first sleeve is caused to close together or open out said flaps.

2. The combination of a stem and a mop head carried thereby, with a sleeve adapted 20 to slide on said stem and a wringing attachment carried by said sleeve, said wringing attachment including members adapted to be opened out or closed together, a second sleeve sliding on said first mentioned sleeve, 25 a spring tending to hold said second sleeve drawn up on said first sleeve, a catch adapted to hold said second sleeve when pressed down over said first sleeve against the action of said spring and connections from 30 said second sleeve to the opening and closing means forming part of the wringing attachment.

3. The combination of a stem and a mop head carried thereby, of a wringing attachment including members which are adapted 35 to be opened out or closed together as required, a sleeve carrying said wringing attachment and slidable on the mop stem, a second sleeve slidable with respect to the first sleeve, connections from said second sleeve to the members of the wringing attachment which open and close, spring means tending to move said second sleeve with respect to the first sleeve in a direction 40 such as to open said wringing attachment, a catch adapted to hold said second sleeve in the position which it occupies when said wringing attachment is closed, and means for releasing said catch when required.

50 4. The combination of a stem with a dome-shaped cap secured at one end of the stem,

a mop head formed of textile material secured in said cap and a wringing attachment 55 slidably mounted on said stem, said wringing attachment including a casing and flaps adapted to be opened and closed over the mouth of the casing, with means for holding the flaps closed or for holding them in the opened position.

5. The combination with a mop head and a stem carrying the same, of a wringing attachment including members adapted to be opened and closed and a support therefor, a sleeve carried on the mop stem connected 60 with said support, and a second sleeve slidable with respect to the first sleeve, connections from said second sleeve to the members of the wringing attachment which are adapted to be opened and closed, a spring 65 engaging between said two sleeves in such manner as to tend to lift up the second sleeve with respect to the first and to hold open the members of the wringing attachment, a catch carried by said second sleeve and a 70 projection on said first sleeve with which the catch is adapted to engage when the movable members of the wringing attachment are closed, a third sleeve slidable with respect to the second sleeve having a face 75 thereon formed in such manner as to press the catch out of engagement when the third sleeve is pressed into the second sleeve, and a flange on the end of the third sleeve adapted 80 to bear against the spring engaging between the first and second sleeves when the catch is released so that the spring action is exerted both against the third sleeve and against the second sleeve.

6. A wringing attachment for a mop, 90 comprising a shell, a pair of flaps pivotally connected to said shell, a sleeve connected to said shell, a second sleeve slidable upon the first sleeve, links connecting said second sleeve to said flaps, spring means tending to pull up said second sleeve with respect to the first sleeve, and thus to hold said flaps open, a catch device adapted to hold said second sleeve when pressed downward into a position in which said flaps are closed, 95 and means for enabling said catch to be disengaged when required.

RICHARD ZIESCHANG.
